UNITED STATES PATENT OFFICE.

URIAH MCCLINCHIE, OF NEW YORK, N. Y.

HAND-STRAP.

SPECIFICATION forming part of Letters Patent No. 659,412, dated October 9, 1900.

Application filed March 30, 1900. Serial No. 10,777. (No model.)

To all whom it may concern:

Be it known that I, URIAHS MCCLINCHIE, a citizen of the United States, residing at New York, (Brooklyn,) in the county of Kings 5 and State of New York, have invented new and useful Improvements in Hand-Straps, of which the following is a specification.

This invention relates to certain improvements in that class of devices known as "hand-straps" and used in street and other railway coaches as a handhold or support for passengers who are compelled to stand; and the invention consists of the combination, with said strap, of a frame or holder or other device and means whereby it is readily attachable directly to the strap at a point between its ends and provided with a plate or card which is removably contained within the frame or holder and has printed, impressed, or affixed to it an advertising subject-matter.

In the accompanying drawings, in which similar letters of reference indicate like parts in the several views, Figure 1 is a perspective view of a suspended hand-strap embodying my invention. Fig. 2 is an enlarged sectional view of the attachable frame or holder.

The strap A is of any appropriate length and material, and its ends are brought together and connected to each other and to the opposite side or member in any appropriate and well-known manner to form upper and lower loops, one of which, A', receives the usual rail or rod which extends along the upper portion of the car, while the other loop A² hangs within easy reach of the passenger standing in the aisle and may be grasped by him to serve as a support.

This strap is provided with holes or eyelets a, which serve as a means for securing and adjusting the height thereon of the frame or holder I will now describe. This frame or holder B is made of any desired material, as aluminium or other metal, or, preferably, leather, fabric, or other flexible material, and through its outer face is cut an opening C, which exposes the plate or card D beneath. The frame or holder is formed with a pocket b, in which the plate or card D is slipped edgewise, and said plate or card will contain some form of advertising matter. At opposite ends the frame or holder is provided with holes or eyelets E, by which said frame is attached to the strap by fasteners c c'. The fastening devices may be studs or even rivets; 55 but I prefer some form of pronged fastener,

which enables the frame or holder to be readily removed from one position on the strap and put into a different position, because of the facility with which the prongs engage the eyelets in the strap. The well-known detachable devices used for fastening sheets of paper together may be used, because of their bendable tangs, they forming a simple and convenient means for engaging and disengaging the eyelets in the upper loop of the strap, or 60 the prongs may be embedded in or permanently secured to the frame, the operation and result obtained being the same in either instance. The upper fastener also serves to secure the card or plate in place by closing the 65 entrance to the pocket in the frame or holder.

The device shown and described is simple and cheaply constructed, and when in place the advertising subject-matter is plainly visible and may be read without difficulty by the 70 passengers, especially by the one who is standing and holding onto the strap. The device shown also makes it possible for me to attach the advertising feature to the straps now in use in the cars and to readily remove and replace the frame or holder without injury to or modification of said straps and to adjust said frame or holder to different vertical heights on the strap with but little difficulty.

Having thus described my invention, what 75 I claim as new, and desire to secure by Letters Patent, is—

An advertising hand-strap consisting of a flexible strap having its ends brought together and united near its center to form two 80 closed loops, a holder on the outer face of the strap between the loops and over the joint of the strap, and formed of flexible material, said holder having its greatest length in the direction of the length of the strap and having a width greater than that of the strap, the 85 holder also having an internal pocket with a flexible entrance in one end thereof to permit the removal and replacement of cards, and devices for detachably securing the flexible 90 holder to the strap, one of said devices also securing the open end of the holder.

In testimony whereof I have hereunto set my hand in presence of two subscribing witnesses.

URIAH MCCLINCHIE.

Witnesses:
